UNITED STATES PATENT OFFICE

149,294

DESIGN FOR A DISPLAY STAND OR SIMILAR ARTICLE

Monroe H. Newman, Brooklyn, N. Y., assignor to Duranol Products, Inc., Brooklyn, N. Y., a corporation of New York

Application November 19, 1946, Serial No. 134,899

Term of patent 3½ years

(Cl. D80—9)

To all whom it may concern:

Be it known that I, Monroe H. Newman, a citizen of the United States, residing at Brooklyn, in the county of Kings and State of New York, have invented a new, original, and ornamental Design for a Display Stand or Similar Article, of which the following is a specification, reference being had to the accompanying drawings forming part thereof.

I claim:

The ornamental design for a display stand or similar article, as shown.

MONROE H. NEWMAN.
